912X Oli Barnum and Benjamin Brody
Letters Patent. July 15, 1803.

The Schedule referred to in these Letters Patent to making part of the same, containing a description in the words of the said Oli Barnum & Benjamin Brody themselves of their Skill.

A new device or improvement of a machine for distilling or boiling water or any kind of liquors. This machine consists of a cylinder, tube, cap and pipe. The cylinder may be made of any kind of wood, and of such size as shall be agreeable to the manufacturer. The cylinder must be gauged from the center to the upper part, so as not to leave a space across the top of the cylinder exceeding 18 inches. A brass or copper cap covers over the top of the cylinder, & connects with a common copper or brass tube about 10 inches square projected downward from the bottom of the cylinder. The pipe enters the tube & passes thro' a flue or oven, then turns upright or vertical until it rises within six inches of the top of the cylinder, then passing into the cylinder. The size of this pipe must vary according to the size of the cylinder. A cylinder containing one hundred gallons. The pipe must be eighteen inches in circumference, that part which rests in the flue. The other part of the pipe may be reduced to one half of that size above mentioned. This pipe may be made of any kind of metal. At the bottom of the tube is a brass cock or faucet where the whole contents may be discharged when it is necessary. When the parts described are exposed to a heated flue the liquor will circulate with great rapidity through the cylinder and pipe.
